(57) **CLAIM**

An ornamental design for an circuit board for an integrated ozone laundry system, as shown and described.

DESCRIPTION

FIG. 1 is a front perspective view of an circuit board for an integrated ozone laundry system according to the present disclosure;

FIG. 2 is a front elevation view of the circuit board for an integrated ozone laundry system shown in FIG. 1;

FIG. 3 is a bottom perspective view of the circuit board for an integrated ozone laundry system shown in FIG. 1; and,

FIG. 4 is a bottom elevation view of the circuit board for an integrated ozone laundry system shown in FIG. 1.

The broken lines shown on FIGS. 1-4 illustrate unclaimed details only and form no part of the claimed design.
